UNITED STATES PATENT OFFICE.

RICHARD A. BRIGHT, OF PROVIDENCE, RHODE ISLAND, ASSIGNOR TO
WALTER A. PECK, TRUSTEE, OF SAME PLACE.

FILLER MATERIAL FOR CIGARS.

SPECIFICATION forming part of Letters Patent No. 398,877, dated March 5, 1889.

Application filed August 18, 1888. Serial No. 283,134. (No model.)

To all whom it may concern:

Be it known that I, RICHARD A. BRIGHT, a citizen of the United States, and a resident of Providence, in the State of Rhode Island, have 5 invented a new and useful Improvement in Filler Material for Cigars, of which the following is a specification.

Cigars, as is well known, are tapered more or less at the point end, the amount and character of such taper varying according to the style of the cigar. In some cigars the taper of the point is short and abrupt. In others such taper is gradual and extends back a considerable distance from the point end of the 15 cigar. The tuck end of the cigar, though sometimes made practically straight and of the same diameter as the body, is now very generally, and especially in the better class of cigars, made more or less tapering, and the amount of this taper at the tuck end also varies in different styles of cigars. Thus the cigar is of the largest diameter at the middle or body section and of less diameter along the point and tuck sections, the diameter of 20 these portions gradually lessening, according to the predetermined taper or form to be given to the point and tuck of the cigar, respectively. Consequently a greater quantity of tobacco measuring transversely is required to 25 properly form the body-section of the cigar and a less quantity to form the tapered ends.

Heretofore in the manufacture of long-filler cigars the method employed for furnishing the required amounts of tobacco and for producing the different diameters at the several 35 sections of the bunch to secure the formation of the proper taper at the point and tuck ends of the cigar has been to build up the bunch at the body-section with short pieces, the uniform practice being to arrange the filler leaves or cuttings in the hand in about the quantity required for a single cigar, and then to break off the projecting ends of the leaves and place them in the middle of the bunch, and thus 40 furnish that part of the bunch which is to form the body of the cigar with a greater quantity of tobacco than there is at the ends, the amount and character of this building up depending upon the style of the cigar to be 45 made. By this method the proper formation 50 of the bunch of fillers and the quantity of

tobacco to be obtained in the several sections thereof depended solely upon the feel or touch of the maker, and to properly gage the required amounts of tobacco at the different 55 portions of the bunch to enable a cigar having the desired tapering point and tuck to be made therefrom, and especially to secure uniformity in the formation of successive bunches, so that the cigars made therefrom 60 would correspond in shape and style, great skill and long practice were required. Furthermore, by this method each bunch of fillers requires to be separately prepared and gaged not only at its middle, but at its ends, 65 and it has been impossible to prepare the fillers in quantity. Even when it has been attempted to make long-filler cigars by machinery it has been necessary to practically gage the fillers bunch by bunch preparatory 70 to inserting into the machine by building up the middle of each bunch the same as when the bunches were to be made into cigars by hand, and the time required for the operator to thus prepare and gage the bunches has 75 heretofore prevented the manufacture of long-filler cigars with profit by machinery.

The object of my invention is to provide cigar-fillers so prepared that in the formation of bunches therefrom for the manufacture of 80 cigars said bunches can be made to contain the required amount of tobacco at the several sections of the bunch with the exercise of much less skill on the part of the maker and in much less time than heretofore; and my 85 invention consists in prepared fillers for cigars, in which the filler-leaves have been prepared by cutting out or removing a portion of the tobacco at the end of the same, so that as the result there will be a less quantity of 90 tobacco at those portions of the fillers which are to form the tapering end of the cigar than at those portions which are to form the body of the cigar, and by properly varying and proportioning the amount of tobacco cut out 95 or removed to that which is retained the fillers may be so prepared as to be adapted to form cigars of any desired shape or contour.

Figure 1 is a top view of a layer of cigar-fillers, showing the primary parallel arrangement of the cuttings or filler-leaves and the line of the cut to be made for removing the 100

surplus tobacco from the end of the fillers. Fig. 2 represent a top view of a layer of prepared fillers, the surplus tobacco having been removed from the ends of the fillers.

5 In the accompanying drawings, A, Fig. 1, represents the top of a layer of cuttings or fillers, such as are usually employed for making long-filler cigars, the said fillers being arranged approximately parallel with each 10 other in any convenient quantity. To prepare the fillers so arranged for the formation of the tapering point of the cigars to be made therefrom, a cut, as shown by the zigzag line *a*, is made at or near the edge of the layer A, 15 the purpose of such cut being to remove a proportionate quantity of the tobacco at that portion of the cigar-filters which are to form the point end of the cigar. This cut is preferably made of tapering or zigzag form, as 20 shown, so that a greater quantity of tobacco will be removed at the extreme ends of the finished fillers than farther in toward the center of the layer, so that as the result of the cut there will be the least tobacco left at 25 the extreme end of the fillers, the amount of tobacco left gradually increasing toward the center of the layer, whereby the fillers will be better adapted for forming the tapering point of the cigars, as will be readily understood 30 from the drawings, and it will be seen that by properly regulating the amount and depth of the cut made the fillers may be prepared so as to provide for the formation therefrom of cigars with any desired form or amount of 35 taper at the point.

If it be desired to prepare the fillers for cigars which are to have tapering tucks as well as tapering points, a similar cut, as shown by the zigzag line *b*, may be made to remove 40 the required amount of tobacco at the opposite end of the fillers. The layer of fillers after both cuts have been made and the surplus tobacco removed is shown in Fig. 2, which represents the fillers B prepared for the 45 formation of cigars with both tapering points and tapering tucks, the fillers as represented being substantially the length of a cigar.

To make cigars by hand from these prepared fillers, the workman has only to take 50 from the layer a quantity of fillers sufficient

to form a bunch of the proper size at the body-section, or place of greatest diameter, and to properly gage the size of the bunch at the body-section by reason of the fact that the proper proportions of tobacco have been previously removed at the end of the fillers, and a cigar of the proper form and taper can be immediately made from such fillers without the necessity of building up the middle or of gaging the form or diameter of the point and 55 tuck ends of the cigar. It is evident that by the use of such prepared fillers much less skill will be required to properly form a cigar therefrom, and consequently a cheaper grade of help can be employed to advantage. 60

The primary arrangement of the fillers in parallel position being a very simple matter, and as by the employment of a properly-formed cutter the required cuts can be speedily made, the cost of manufacturing long- 70 filler cigars by hand can be very much reduced, and at the same time much greater uniformity can be secured.

Fillers prepared as above described are also especially adapted to be fed automatically to 75 a cigar-bunch machine, and, inasmuch as the fillers can be so prepared at a small fraction of the cost of arranging fillers to be fed into a machine by the methods heretofore employed, the use of such tapered fillers makes 80 possible the profitable manufacture of long-filler cigars by machinery.

I do not in this application claim the method of preparing filler material for the manufacture of cigars as herein described, the same 85 having been described and claimed by me in my pending application, Serial No. 275,847.

I claim as my invention—

A prepared mass of cigar-filters having a portion of the tobacco cut out or removed at 90 the edge of the mass, so that a quantity taken from any portion of said mass will contain the proper proportion of tobacco in its different parts to form cigars of the required shape or taper.

RICHARD A. BRIGHT.
